UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

ELECTRIC CONNECTER.

Application filed March 26, 1925. Serial No. 18,395.

My invention relates to electric connectors of the general class in which a detachable plug carrying a set of wire terminals is mounted in a socket carrying another set 5 of terminals, and in which the terminals of the two sets are normally held in contacting relation. Connecters of this class as employed on automobiles have commonly been constructed with bayonet slots formed 10 on the shell of the socket and interlocking with projecting pins on the wire-carrying plug. In practice, such a bayonet joint arrangement is objectional for many reasons, one being the looseness of the connected 15 parts, which looseness not only leads to rattling noises but sometimes even permits the interlocking pins to be shaken out of the bayonet slots. Another objection is due 20 to the ready entrance of dust and moisture into the space between the plug and the terminal-carrying body member of the socket, thereby allowing the dust to interfere with the adequate contacting of the wire terminals and either interrupting the circuit or 25 causing a sparking between the contacts.

To allow for the partial retraction of the plug after its insertion in the shell, as is required with a bayonet slot construction, it is also necessary to employ spring means 30 for keeping the contacting terminal portions in engaging relation. Heretofore, the needed spring means have commonly been provided by using spring-pressed plungers as the contacting portions of the wire terminals on either the socket or the plug, thereby depending partly on springs for carrying the current and partly on a circuit connection through relatively slidable parts. Or, where the wire terminals of the socket 35 have been mounted on a spring-pressed body slidable in a socket shell, the sliding arrangement has not permitted the several terminals of the socket to adjust themselves independently so as to compensate for any lack of 40 uniformity in size or shape of various parts of the socket and the plug. Owing to this fact, such a construction often affords a poor contact or connection to one wire, this being particularly noticeable with connectors employed for making electrical connections to more than two wires. So also, since 45 the plug of a connector has to be partially rotated in attaching it to a socket when a bayonet joint is employed, the plug terminals tend to catch on the socket terminals,

and if one of the terminals projects unduly, a careless user may use so much force as to damage some of the parts of the connector.

My invention aims to overcome all of the above named objections to the connectors heretofore employed, while also providing a strong, inexpensive and compact connector construction. With this in mind, my invention provides a connector which will permit a rigid fastening of each set of wires to metal terminals contacting directly with the terminals of other wires, thereby avoiding the necessity of having any current pass through slidably connected parts or through springs. My invention also provides spring 70 means for effectively maintaining the engagement of the associated contact terminals, provides a construction for this purpose which will readily permit the use of relatively large springs, provides for the independent adjusting of the contacts between each engaging pair of wire terminals, and provides simple means for preventing the contacts on the socket from shifting out of proper alignment with the contacts carried 75 by the plug.

Furthermore, my invention provides simple and effective means for rigidly supporting such a connector, provides means associated with the plug for connecting the 80 plug to the casing of an armored cable which carries the wires to the plug, and provides a connector which is entirely sealed against the entrance of dust. It also provides a construction in which a tubular supporting member can readily be secured to the support for the socket portion of the connector and in which the other parts can 85 readily be attached to (or detached from) this supporting member, and provides simple means for preventing a detaching of the socket proper from the supporting member during the attaching of the plug or 90 while the plug is detached.

Still further and also more detailed objects will appear from the following specification and from the accompanying drawings, in which—

Fig. 1 is a side elevation of a connector embodying my invention, showing this as 105 it appears when attached to a supporting plate through which it extends.

Fig. 2 is an end view of the same connector, taken from the left hand of Fig. 1.

Fig. 3 is an enlarged view taken from the 110

top of Fig. 1, with the tubular supporting member and the plug sleeve in central and longitudinal section.

Fig. 4 is a central and longitudinal section taken at right angles to Fig. 3, with a portion of the insulating body of the plug left unsectioned.

Fig. 5 is a section taken transversely through Fig. 4 along the line 5—5.

Fig. 6 is a section similar to Fig. 5, showing the arrangement of the insulating parts and the wire terminal heads of the socket of my connector in a three-wire form.

Fig. 7 is a perspective view of one of the insulating parts of the socket of Figs. 4 and 5.

Referring to the embodiment of Figs. 1 to 6 inclusive, this includes a supporting member in the form of a cylindrical tube 1 adapted to extend through a corresponding perforation in a support, such as a plate 2, and having intermediate its end a peripheral bead 3 adapted to engage the rear face of such a support while the forward end of the tube 1 is flared outwardly to form a flange 4 engaging the forward face of the support, thereby clamping the tubular supporting member rigidly to the support.

Slidably inserted into this tubular supporting member from the rear thereof is a socket shell having a cylindrical wall 5 fitting the bore of the tubular member. This wall 5 has near its rear end three outwardly projecting fingers which are slidably received by corresponding slots 7 in the tubular member 1, so as to prevent the socket shell from rotating in the rigidly supported tubular member, and so that the engagement of these fingers with the forward ends of the said slots will limit the forward sliding of the socket shell into that member. The tubular member also is provided near its rear end with a pair of perforations spaced circumferentially of this member, so that a fastening element (shown in Figs. 1 and 2 as a spring cotter 8) can be inserted through these perforations behind the rear end 9 of the socket shell to prevent this shell from being rearwardly slid during the attaching of the plug parts.

The shell end 9 has perforations corresponding in number to the number of wires to which circuit connections are to be provided, namely two in the case of the double pole form shown in Figs. 1 to 6. Each of these wires 10 is connected at its forward end to a contact 11 which forms the corresponding wire terminal of the socket, this contact being here shown as the head of a tack having its stem inserted between the strands of the core of a corresponding wire 10. Each of the wire terminals is supported in a fixed position transversely of the socket shell by means permitting it to be moved longitudinally of the socket independently

of the other wire terminals. For this purpose, I am showing each of the contacts (or tack heads) 11 as seated on an annular shoulder 12 forming the bottom of the enlarged upper portion of a bore 13 which extends longitudinally through an insulator 14 disposed within the socket shell, and am showing the wire as expanded by the stem of the tack so as to wedge it in the bore 13.

Each of the insulators has its main portion formed as a semicylinder 14 corresponding in diameter to the bore of the cylindrical socket shell 5, and the two insulators have their flat longitudinal edges abutting against each other as shown in Fig. 5. Each insulator also desirably has on its arcuate edge an outwardly directed projection 15 which extends into a longitudinal slot 16 of corresponding width in the socket shell, so that the longitudinal walls of the slots engage the projection to prevent rotational movement of the insulator about the axis of the socket. Interposed between each of the insulators 14 and the rear end 9 of the socket shell is a compression spring 17, the insulator desirably having its said bore 13 enlarged in diameter at its rear end so as to afford an enlarged bore portion housing the spring for a part of its length as shown in Fig. 4. Each of these springs continuously urges the adjacent insulator forward of the socket independently of the other insulator, as the abutting edges (which are disposed in a plane diametric of the socket) permit the insulators to slide on each other. Moreover, each slot 16 has its forward end wall disposed so as to engage the projection 15 on the adjacent insulator to limit the forward movement of this insulator by the spring which presses against it.

Extending into the socket shell from the front or mouth end thereof is an insulator in the form of a cylinder 18 which carries the wire terminals for the other set of wires 19. This insulator also has the wire terminals rigidly fastened to it, the terminal being here shown as comprising a screw 20 having its head exposed behind the insulator 18 and directly engaging one of the contacts 11 of the socket, a body member 21 threaded at one end upon the screw 20 and provided at its other end with a loop 22 through which a free end of the core of the wire 19 is hooked, and a screw 23 arranged for clamping this hooked portion of the wire against the bight of the loop. The insulating cylinder is slidable in the socket shell, but is kept from rotating in this shell by a pin 30 fast on the cylinder and projecting into a longitudinal slot 31 in the socket shell, as shown in Fig. 3.

Bearing against the front end of the insulating cylinder 18 is an annular flange 24 on the rear end of a ferrule 25 through which the wires 19 extend. This flange is

overhung by an inwardly directed annular flange 26 on a plug sleeve 27 which has its rear end portion threaded on its interior so as to be screwed upon the forward portion 5 of the socket shell 5. This sleeve 27 has its rear end normally engaging the forward end of the tubular supporting member 1; for which purpose the sleeve desirably has at 10 its rear end an outwardly directly annular flange 28.

With the parts thus arranged, it will be seen from Fig. 4 that when the sleeve 27 is screwed upon the forward end of the socket shell, the flange 26 will press rearwardly 15 through the flange 24 of the nipple against the insulating cylinder 18, thereby sliding this insulator rearwardly against the pressure exerted through the springs 17 and the semi-cylindrical insulators 14 on the wire 20 terminals, the parts being so proportioned in length that the springs 17 will be somewhat compressed before the flange 28 of the plug sleeve 27 engages the forward end of the tubular supporting member. This engagement 25 of the plug sleeve with the supporting member limits the extent to which the springs are compressed, so as to prevent the springs from being over-strained or entirely collapsed. It also locks the sleeve 27 30 against accidental rotation and holds the various socket parts firmly assembled so that there will be no rattling.

Furthermore, the said engaging of the flange 28 with the supporting member, together with the clamping of the nipple flange 24 between the insulating cylinder and the forward end flange 26 of the plug sleeve prevent the entrance of dust into the sleeve, while the forward end of the nipple 40 25 can readily be sealed by a suitable taping of the wires 19 or by soldering the nipple to the casing 29 of an armored cable of which the wires 19 form a part. Consequently, the entire forward end of the connector is effectively sealed against the entrance of moisture and dust, which was not possible with connector and plug constructions of the bayonet slot type. So also, since the various 45 portions of the casing are firmly clamped together, all looseness or rattling is avoided, and the sleeve 27 can readily be screwed up so tightly against the forward end of the tubular supporting member as to guard 50 against an accidental loosening. To facilitate the needed rotating of the plug sleeve, I desirably knurl this near its forward end, as shown at 32 in Fig. 1.

To facilitate the assembling of the socket, I desirably bevel the rear portions of the 60 diametric flat edges of the semi-cylindrical insulators 14 as shown in Fig. 4, thereby enabling me to insert one of these insulators in the shell 5 after the other has been placed in position. When the connector is 65 completely assembled, the providing of separate

insulators respectively secured to the several wire terminals of the socket portion of the connector permits these insulators to slide independently of each other longitudinally of the connector, thereby compensating for 70 any variations in the lengths of the contacting portions of the associated terminals or in the mounting of the latter, and permitting each spring to effect a firm contacting of the two wire contacting terminals with which 75 it is associated. Owing to this provision, my connector is particularly suited for use with heavy currents, such as those encountered with connectors used on automobile trucks. 80

However, I do not wish to be limited to the various details of the construction or arrangement here disclosed, it being obvious that many modifications might be made without departing either from the 85 spirit of my invention or from the appended claims. Neither do I wish to be limited to the use of my invention in connection with double-pole connectors, as the same underlying principles may also be employed advantageously for making the connections to a larger number of wires. For example, Fig. 6 shows the insulating socket parts as comprising three sectors which when assembled will correspond to a cylinder 90 slidably fitting the bore of the socket shell, each insulating sector having an outwardly directed projection 15 entering a corresponding longitudinal slot in the socket shell 5. In either case, I desirably make 100 the insulating parts of the socket portion of my connector of a considerable length, thereby securing an extensive bearing of these parts both on the socket shell and on each other, so as to prevent the insulators 105 from being tilted. By extending the springs into such relatively thick insulators, I shorten the length required between the backs of the insulators and the rear end of the socket shell, thereby still securing a 110 compact construction. Moreover, the shortness of each wire portion between the shell end and the part of the wire fastened to the insulator prevents any material bending of that wire portion, thus cooperating with the 115 friction of the spring on the shell end in preventing rotational movement of the sectional insulating member in the socket shell. Hence the projections 15 on the insulators might be omitted, though I preferably employ them so as to permit an easier sliding of each wire through a shell end perforation of a diameter closely approaching that of the wire. 120

Since the projections on the insulators of 125 the socket prevent the assemblage of insulators from rotating in the socket shells, the socket wires 10 are always maintained in the same positions rotationally of the socket shell. Consequently, these wires can extend 130

slidably through rear end perforations in the shell closely approximating the outside diameter of the wires, thereby substantially sealing the rear end of the shell also against

5 the entrance of dust and moisture.

Moreover, since the socket portion of my connector is detachably held in position in the tubular supporting member by the spring cotter, all other parts of the connector can 10 readily be attached to this supporting member after both sets of wire terminals have been connected to the corresponding wires. This makes it easy for the user to wire the connector proper, as also to detach the same 15 from the supporting member for an inspection of the connector parts at any time.

I claim as my invention:—

1. In a connector, a tubular supporting member, a connector shell slidably inserted 20 into the supporting member from the rear of the latter; the said member and shell having cooperating formations engaged during the said slidable insertion for preventing relative rotation of the said members and 25 for limiting the forward sliding of the shell with respect to the supporting member; and clamping means threaded on the shell and engaging a forward portion of the supporting member to prevent rearward movement 30 of the shell.

2. A connector as per claim 1, in combination with two sets of relatively interengaging wire terminals disposed in the shell, and means actuated by the screwing of the clamping 35 means on the shell for forcibly approaching one set of wire terminals to the other.

3. A connector comprising a shell open at its forward end, a pair of wire terminals 40 slidably supported in the shell for slidable movement longitudinally of the shell, two spring means respectively urging the said wire terminals forwardly; an insulator extending slidably into the shell from the forward end thereof, a second pair of wire terminals 45 mounted on the insulator and respectively engaging the first named wire terminals, and means threaded on the shell for forcing the insulator rearwardly; in combination with a tubular support in which 50 the shell is slidably mounted, and cooperating stop means on the shell and support for limiting the forward sliding of the shell with respect to the support; the threaded means having a portion engaging the tubular support, whereby a rotation of the 55 threaded means (in the direction in which the latter forces the insulator rearwardly)

will slide the shell forwardly with respect to the tubular support so as to force the said cooperating stop means into engagement.

4. In a socket or connector, a shell, a pair of laterally adjoined insulators corresponding in joint contour to the bore of the shell and having their contiguous edge portions disposed in a plane diametric of the shell, the insulators being independently slidable longitudinally of the shell, the shell having a pair of longitudinal slots and each insulator having a projection slidably housed by one of the said slots, a pair of wire terminals respectively fast on the insulators, and a pair of coiled springs each interposed between one of the insulators and a part of the shell and each arranged for urging the corresponding insulator and wire terminal away from the said part of the shell independent of the other insulator and wire terminal.

5. A connector comprising a shell having 80 a substantially cylindrical lateral wall and a rear end provided with a plurality of perforations, a plurality of laterally adjoined insulators conforming conjointly in peripheral contour to the bore of the shell and 85 loosely held in laterally adjoined relation by the said bore, the insulators having adjoined edges in planes diametric of the shell and being independently slidable longitudinally of the shell and each having a bore 90 alining with one of the perforations in the shell end; wires respectively extending slidably through the said perforations and each extending into the insulator bore which alines with the corresponding perforation, 95 wire terminals respectively projecting forwardly from the several insulators and each rigidly securing the free end of one wire to the insulator beyond which that wire terminal projects, and compression springs each 100 interposed between the rear shell end and one of the insulators; the distance between each insulator and the rear shell end being so short as to prevent a material bending of the wire portion between that insulator and 105 the rear shell end, thereby cooperating with the slidably engaging of the shell end perforations by the wires and the said adjoining of the insulators in preventing the insulators from moving rotationally of the shell.
